UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

FUSIBLE DEVICE FOR AUTOMATIC FIRE EXTINGUISHERS OR APPLIANCES.

1,117,411.

Specification of Letters Patent.

Patented Nov. 17, 1914.

Application filed November 16, 1909. Serial No. 528,295.

To all whom it may concern:

Be it known that I, ALBERT J. LOEPSINGER, of the city and county of Providence and State of Rhode Island, have invented certain 5 new and useful Improvements in Fusible Devices for Automatic Fire Extinguishers or Appliances; and I do hereby declare the following specification, taken in connection with the accompanying drawings, forming a 10 part of the same, to be a full, clear, and exact description thereof.

So called fusible links, or more properly links composed of two more members united by fusible solder, are commonly employed 15 in the fire extinguishing art for holding the valve of an automatic sprinkler closed, for holding fire doors, and for other purposes.

The present invention relates to fusible devices of this character, and has for its object to provide a fusible device of improved 20 construction.

To this end the invention consists primarily of a fusible device the two main members of which are each provided with 25 laterally projecting flanges.

The invention further consists of a fusible device the two main members of which are each provided with a semi-circular recess and with a laterally projecting flange at one or 30 both ends of such recess.

The invention further consists in the features of novelty and construction hereinafter described and claimed.

Referring to the drawings, Figure 1 is a 35 perspective view of my improved fusible device, and Fig. 2 is a central longitudinal section of the same.

The device comprises two overlapping members A, A, and an interposed part B, 40 preferably in the form of a hollow cylinder or roller. These parts are all united by an easily fusible solder.

Each of the members A is provided with a semi-circular recess to receive the roller B, 45 and each of said members is also provided at its opposite edges with laterally projecting flanges a, a. As shown in the drawings, these flanges are located one at each end of the semi-circular recess a, said flanges being 50 preferably more or less semi-circular in form, as shown. If desired, however, said flanges can be otherwise located, or each flange may extend a larger part of the length of the member A. So also, if desired,

each member A may be provided with such 55 laterally projecting flange on only one of its edges, or at one end only of its semi-circular recess.

When the device is to be used as a link each member A is provided with an aperture a', to receive a part of the valve-holding device of the sprinkler or to receive a wire or other holding device. When the device is to be used as a strut, as it may be, these apertures a' are preferably omitted 60 and in such case the outer ends of the members A will be preferably more or less squared or otherwise suitably formed.

The operation of the device will be readily understood by persons skilled in the art. 70

When the device is subjected to the action of heat and the solder is thereby fused the pulling strain to which the device is subjected when used as a link, or the pushing strain to which it is subjected when used as 75 a strut, will cause the semi-circular portions of the members A to ride up the curved surface of the roller B on opposite sides thereof, and the wedging action thereby produced will cause the members A to be laterally 80 separated from each other, which will result in rupturing the solder and thus release the members A and the parts which may be connected therewith. In addition to the wedging action of the roller B above referred to, there is also a certain rolling action of said roller which serves to increase 85 the separating movement of the members A and correspondingly facilitate the rupture of the solder-joint. The employment of the 90 flanges a, a is accompanied by several important advantages. In the first place said flanges serve to strengthen the members A, and especially when said members are provided with the semi-circular recesses to receive the roller B. Thus when a member A is provided with such semi-circular recess there is a tendency, especially under the action of a pulling strain, to straighten more or less the semi-circular portion of such 95 member, accompanied by a corresponding tendency to rupture the solder joint. The flanges a, a serve to strengthen the members A and to resist the tendency of the semi-circular portion to straighten under strain. 100 Thus by the employment of such flanges the device will be able, when the members are made of material of a given thickness, to

105

withstand a greater strain without weakening or destroying the solder-joint than would be the case if such flanges were not present, or on the other hand, in order to 5 withstand a given strain, the members A when provided with such flanges may be made of a correspondingly thinner material, thereby reducing the cost of the device. Moreover a reduction in the thickness of the 10 material of which the members A are composed not only serves to thus reduce the cost of the device, but also serves to increase its efficiency, as the thinner the material of the members A the more sensitive will the device be to the action of heat upon the fusible 15 solder. Another advantage resulting from the employment of said flanges is the increased sensitiveness of the device to the action of heat upon the fusible solder due to 20 the increased area exposed to the heat which is provided by such flanges. In this connection it will be noted that said flanges are so disposed that the heat has direct access to both sides of said flanges as well as to the 25 edges thereof.

As the result of the construction above described, as will be seen, the improved link or device is on the one hand stronger and able to withstand greater strains without injury to the solder-joint when there is no fire, 30 while on the other hand said device is more sensitive to the action of heat and thus more efficient or more prompt in action when a fire occurs.

35 It will be understood, as above pointed out, that the device may be used either as a link to resist a pulling strain, or as a strut to resist a pushing strain or thrust.

It will be further understood that the 40 flanged construction of the two main members A may be employed to advantage in a device comprising only such two main members soldered together and in which the third member or roller B is omitted, although the 45 advantages attending the employment of

such flanges is more fully availed of where said third member or roller B is employed, and the main members A are provided with recesses to receive the same. These recesses, it will be understood, while preferably semi-circular, may, if desired, be of some other shape in cross-section. So also, while it is preferred that the roller B shall be hollow, said roller may, if desired, be made solid. 50

What I claim as my invention and desire 55 to secure by Letters Patent is:

1. A fusible device for use in automatic fire extinguisher apparatus, comprising two members, each of said members being provided with a transverse recess and with projecting flanges at the opposite ends of said recess. 60

2. A fusible device for use in automatic fire extinguishing apparatus comprising two main members each provided with a recess, 65 and a third member interposed between said main members and located in said recesses, each of said main members being provided with projecting flanges at its opposite edges.

3. A fusible device for use in automatic fire extinguishing apparatus comprising two main members each provided with a recess, 70 and a third member interposed between said main members and located in said recesses, each of said main members being provided 75 with projecting flanges at the opposite ends of the recess therein.

4. A fusible device for use in automatic fire extinguishing apparatus comprising two main members each provided with a semi-circular recess, and a third member in the 80 form of a roller interposed between said main members and located in said recesses, each of said main members being provided with projecting flanges at the opposite ends 85 of the semi-circular recess therein.

ALBERT J. LOEPSINGER.
